UNITED STATES PATENT OFFICE.

JOHN W. KILLINGSWORTH, OF FITZGERALD, GEORGIA.

PUNCHING MACHINE.

Application filed May 31, 1924. Serial No. 717,016.

To all whom it may concern:

Be it known that I, JOHN W. KILLINGSWORTH, a citizen of the United States, residing at Fitzgerald, in the county of Ben Hill and State of Georgia, have invented certain new and useful Improvements in Punching Machines, of which the following is a specification.

This invention relates to punching machines, and has for its primary object, the provision in a manner as hereinafter set forth, of a punching machine particularly designed for punching springs for use upon locomotives and so designed that hanger holes may be punched through the spring leaf cleanly, quickly and without burring the edges of the aperture.

This invention has for another of its objects, the provision of a punching device for use particularly for punching locomotive spring leaves, whereby, simultaneously with the punching of the hanger holes in the spring leaf, a centering hickey is pressed into the leaf, so that upon the assembling of the leaves the hickey will interlock and thus bring the leaves in perfect alignment.

A still further object of this invention is the provision, in a manner as hereinafter set forth, of an improved type of punch for use in connection with a machine of this design, which punch is so constructed as to give a shearing action upon the material to form the aperture therein free of burs about the edge thereof.

A further and final object of the invention is the provision, in a manner as herein-after set forth, of a spring leaf punching machine of strong and sturdy construction, of easy operation, quick and accurate in action, and inexpensive to build.

The invention will be best understood from a consideration of the following detailed description taken in connection with the accompanying drawings forming part of this specification with the understanding, that this invention is not confined to any strict conformity with the showing of the drawings, but may be changed and modified so long as such changes and modifications mark no material departure from the salient features of the invention as expressed in the appended claims.

In the drawings:

Figure 1 is a side elevation of the machine embodying this invention. 55

Figure 2 is a transverse sectional view upon the line 2—2 of Figure 1.

Figure 3 is a transverse sectional view upon the line 3—3 of Figure 1.

Figure 4 is a sectional view upon the line 4—4 of Figure 1. 60

Figure 5 is a section taken upon the line 5—5 of Figure 3.

Referring now to the drawings in detail wherein like numerals of reference indicate corresponding parts throughout the several views of the drawings, numeral 1 indicates a support of any suitable construction. 65

A base 2 of substantial length and width is provided, and this base is preferably formed of channel iron as indicated. 70

Extending upwardly from each end of the base iron 2 is a standard 3 also preferably of channel iron, and the upper end of each of the standards 3 is bent inwardly 75 at an obtuse angle as indicated at 4 to provide the inwardly extending opposed arms 5. The free end of each of the arms 5 is formed to provide a flat plate 6 as shown.

Centrally supported in vertical position between the plates 6 of the arms 5 is a compressed air piston cylinder 7 having formed upon the wall thereof bosses 8 to receive the inner face of the plates 6 which are secured thereto by the rivets or other appropriate securing means 9. Removable plates 10 and 11, respectively, are secured by means of bolts 12 to the upper and lower end of the cylinder to close the same, the upper plate 10 having an exhaust valve 13 80 and an air inlet pipe line 14 extending therethrough while the lower plate 11 has an exhaust valve 15 and an air inlet pipe line 16 entering therethrough and in addition a centrally positioned annular collar 17 is formed upon the face of this plate having a central bore therethrough and having an annular flange 18 at the lower edge thereof. A packing gland 19 fits into said collar and is secured to the flange thereof 85 by means of a bolt 20.

Working in said cylinder 7 is a piston 21 carrying a piston rod 22 which extends through said collar 17 and gland 19 and projects a substantial distance below the end 100 of the cylinder 7.

The end of the piston rod 22 has an axial bore therein as at 23 to receive the reduced end 24 of a hickey punch 25. This hickey punch is removably secured in position by means of the set screw 26 which is passed through the lower end of the piston rod 22 and engages the reduced portion 24 of the punch. The operation and purpose of this punch will be described further in the specification.

Secured about the piston rod 22 adjacent the lower end thereof is a two-part clamp member indicated as a whole by the numeral 27. This clamp comprises a pair of yoke members 28 and 29 respectively, the arms 30 of one of the yoke members being of greater length than the arms 31 of the other yoke and further being cut in to receive the arms 31 of the yoke 29 so that the outer faces of the arms 31 will be flush with the face of the arms 30 of the yoke 28 as shown in Figure 2. When the yokes are in position about the piston rod 22 bolt securing members 32 are passed through the arms to retain the clamp in position. The extended ends of the arms 30 of the yoke 28 are bifurcated as at 33, and the furcations have formed therein horizontal aligned slots 34 to slidably receive therethrough pivot bolts 35 which pivotally retain one end of toggle arms 36 between the furcations of the bifurcated end 33 of the arms 30.

Secured upon the inner face of each of the standards 3 is a plate member 37 from which extends a pair of spaced ears 38 between which the other ends of the toggle arms 36 are positioned and pivotally held by means of a transversely extending bolt 39. Each of the toggle arms 36 has a longitudinally extending series of apertures 40 therethrough through which there is extended a securing bolt 41 which passes through a bifurcated upper end 42 of a shear punch 43. The furcations of the bifurcated end 42 of the punch 43 are as shown positioned one on each side of the toggle arms and pivotally held in position by the aforesaid bolt.

The shear punch used in connection with this machine is a relatively flat elongated body as shown, the upper end of which is bifurcated as before stated and the lower end is cut in V-shape as is indicated at 44 to provide the pointed cutting members 45. Due to the particular design of this punch, the double cutting edges shear through the body of metal much quicker and easier than with punches of the ordinary construction.

It is to be noted that the brackets 37 which support the outer ends of the toggle arms 36 are positioned slightly below the clamp 27 when the piston 21 is in raised position and the slots 34 in the arms 30 of the yoke 28 being slotted allow the pivot bolts 35 to reciprocate when the punch is operated so

that the toggle arms 36 move to a horizontal position when the punch is in operation and rise to an inclined position when not in use as shown in Figure 1.

Extending beneath the punches 43 and between the standards 3 is a pair of channel irons 46 placed back to back and in spaced relation one to the other as shown in Figure 4. These channel irons are secured by means of brackets 47 to the standards and their top edges which are in the same plane constitute a die table for the machine.

Placed upon and extending lengthwise of the die table 48 provided by the parallel side edges of the channel members 46 is a die plate 49 having extending longitudinally along the rear edge thereof the raised portion 50 which constitutes a spring plate against the inner face of which the spring 51, when placed upon the die plate, abuts to properly position the spring upon the plate. Located intermediate the ends of the die plate 49 is a depression 52 which is directly beneath the point of the hickey punch 29 and into which the punch extends when the same depends toward the die plate. Formed through each end of the die plate 49 is an elongated slot 53 which constitutes the die for the hanger hole which is to be formed in the spring 51 adjacent each end. This aperture or slot 53 in the die plate 49 is elongated as shown to receive the shear punch 43 when the same depends and after it has passed through the spring leaf 51. Secured to the spring leaf gauge 50 adjacent the hanger hole die 53 is a plate member 54 which has formed therethrough an elongated slot 55 of the same size as the hanger hole die 53 and which is in alignment therewith, and this plate and slot constitutes a punch stripper through which the punch must pass before passing into the work and which serves to strip the work from the punch when the same is being withdrawn.

Secured upon the die table 48 at the forward part thereof is a pair of cams 56 having actuating handles 57 by means of which the cams are revolved to engage the edge of the spring which is placed upon the die table to force the same against the gauge 50 and at the same time retain the spring tightly in position after the same has been properly centered.

The operation of the machine thus far described is as follows:

Starting with the piston 21 in raised position as shown in Figure 1, a spring leaf 51 is placed upon the die plate 49 and arranged so that the ends of the punches will be directed toward that portion of the spring which is to be punched out. The arms 57 of the cams 56 are then swung until the cams have bound the spring tightly against the gauge 50 whereupon a valve 58

is opened to admit compressed air from an air pipe line 59 into the pipe line 14 which leads into the top of the cylinder 7. This causes the piston and piston rod to move 5 downwardly actuating the toggle arms 36 to force the shear punches 43 through the spring leaf. At the same time that these punches are being forced through the spring, the hickey punch 25 engages the spring and 10 forms a depression at the upper side thereof at the same time pressing out a portion upon the under side of the spring. When the punches have passed through the spring body and it is desired to remove the same, 15 the valve 58 is closed, the exhaust valve 13 in the top of the cylinder 7 is open, and the valve 60 is then opened to admit compressed air from the pipe 59 through the pipe line 16 and into the lower portion of 20 the cylinder 7 to raise the piston and piston rod and thus withdraw the punches from the work. It is to be noted that at the beginning of the operation, the lower exhaust valve 15 in the cylinder 7 is opened before 25 the valve 58 is opened to admit compressed air into the top of the cylinder. This of course is closed after the piston has reached the limit of its downward stroke and before the valve 60 is opened to force the piston 30 up again.

Supported upon one of the standards 3 upon the outer face thereof is a small cylinder 61 similar in construction to the cylinder 7, this cylinder 61 having an exhaust 35 valve upon the top as at 62 and an air inlet pipe line 63 extending through at its top and also having an exhaust valve 64 and an air pipe line 65 entering the bottom thereof. Located within this cylinder 61 is a piston 40 66, the rod 67 which extends from the piston 66 through the lower portion of the cylinder being pointed to provide a punch 68. Valves 69 and 70, respectively control the air pipe lines 63 and 64 which lead to the 45 top and bottom of the cylinder.

Secured to the standard 3 beneath the cylinder 61 is a bracket 71 which supports thereon a die 72 which is located directly beneath the punch 68. This punch and die 50 is for the purpose of forming hickies in the center of spring plates of smaller size than those formed and punched upon the die plate 49 of the large machine. When all of the 55 spring plates have been so punched by the hickey punch, the plates are very easily assembled, for, upon placing one upon the other the projected portion upon the under side of one spring plate will seat itself into the depression upon the top side of the next 60 lower spring plate and the assembler will then know that all of the spring plates or leaves are in proper position.

From the foregoing description it is to be seen that a very novel punch machine is provided by which plates of heavy metal may

be easily and quickly punched and at the same time so marked that upon assembling they all will properly align themselves.

Having thus described my invention what I claim is:

1. In a punching machine, a pair of spaced vertical standards having their upper ends inturned and in spaced opposed relation, a power cylinder supported vertically between said upper ends, a piston and piston rod working in said cylinder, said rod extending through the lower end thereof, a die table comprising a pair of parallel spaced members positioned between said standards beneath said cylinder, a pair of toggle arms positioned above said table and having their outer ends pivotally connected to said standards and their inner ends slidably and pivotally connected to said piston rod, and punch members pivotally secured to said toggle arms for vertical reciprocation above said table upon actuation of said piston and piston rod. 70

2. In a punching machine, a pair of spaced vertical standards having their upper ends inturned and in spaced opposed relation, a power cylinder supported vertically between said upper ends, a piston and piston rod working in said cylinder, said rod extending through the lower end thereof, a die 80 table positioned between said standards beneath said cylinder, a pair of toggle arms positioned above said table and having their outer ends pivotally connected to said standards and their inner ends slidably and pivotally connected to said piston rod, punch members pivotally secured to said toggle arms for vertical reciprocation above said table upon actuation of said piston and piston rod, said toggle arms having a plurality of longitudinally extending apertures therethrough for the adjustment of said punches longitudinally of said table. 85

3. In a punching machine, a pair of spaced vertical standards having their upper ends inturned and in spaced opposed relation, a power cylinder supported vertically between said upper ends, a piston and piston rod working in said cylinder, said rod extending through the lower end thereof, a die 90 table positioned between said standards beneath said cylinder, a pair of toggle arms positioned above said table and having their outer ends pivotally connected to said standards and their inner ends slidably and pivotally connected to said piston rod, punch members pivotally secured to said toggle arms for vertical reciprocation above said table upon actuation of said piston and piston rod, said toggle arms having a plurality of longitudinally extending apertures therethrough for the adjustment of said punches longitudinally of said table. 95

4. In a punching machine, a pair of spaced vertical standards having their upper 100

ends inturned and in spaced opposed relation, a power cylinder supported vertically between said upper ends, a piston and piston rod working in said cylinder, said rod extending through the lower end thereof, a die table positioned between said standards beneath said cylinder, a pair of toggle arms positioned above said table and having their outer ends pivotally connected to said standards and their inner ends slidably and pivotally connected to said piston rod, punch members pivotally secured to said toggle arms for vertical reciprocation above said table upon actuation of said piston and piston rod, said toggle arms having a plurality of longitudinally extending apertures therethrough for the adjustment of said punches longitudinally of said table, and a hickey punch carried upon the end of said

piston rod adapted to act upon the work simultaneously with said arm carried punches.

5. In a punching machine having means for reciprocating the opposed connected inner ends of a pair of pivoted toggle arms, a shear punch comprising, a relatively broad and substantially elongated member having one end bifurcated for engagement over one of said arms for pivotal connection therewith and further having its other end provided with a substantially V-shaped slot to provide a pair of pointed cutting members, and means for pivotally securing one of said arms between the furcations of one of said bifurcated ends.

In testimony whereof, I affix my signature hereto.

JOHN W. KILLINGSWORTH.
